UNITED STATES PATENT OFFICE

152,653

DESIGN FOR A LADY'S HAT AND SHOE CASE

Nina D. Rinehart, Seattle, Wash.

Application November 5, 1946, Serial No. 134,528

Term of patent 14 years

(Cl. D87—5)

To all whom it may concern:

Be it known that Nina D. Rinehart, a citizen of the United States, residing at Seattle, King County, Washington, has invented a new, original, and ornamental Design for a Lady's Hat and Shoe Case, of which the following is a specification, reference being had to the accompanying drawing, forming a part thereof, in which:

Fig. 1 is a perspective view of a lady's hat and shoe case showing my new design in open position;

Fig. 2 is a rear elevational view, on a reduced scale, of the case shown in Fig. 1 in closed position;

Figure 3 is a side elevational view, on a reduced scale, of the lady's hat and shoe case, as shown in Fig. 2, the other side thereof being identical;

Fig. 4 is a bottom plan view of the same, shown on a reduced scale.

I claim:

The ornamental design for a lady's hat and shoe case, as shown and described.

NINA D. RINEHART.
